The ornamental design for a medical equipment stand for infection control supplies, as shown and described.

DESCRIPTION

FIG. 1 is a perspective view of an embodiment of a medical equipment stand for infection control supplies in a hospital or treatment center of the present invention;

FIG. 2 is a front view of the device of FIG. 1;

FIG. 3 is a back view of the device of FIG. 1;

FIG. 4 is a left side view of the device of FIG. 1;

FIG. 5 is top view of the device of FIG. 1;

FIG. 6 is a bottom view of the device of FIG. 1; and,

FIG. 7 is a right side view of the device of FIG. 1.

In FIGS. 1, 2 & 3 of the medical equipment stand for infection control supplies a symbolic break is shown in the stand's length. The appearance of any portion of the article between the break lines forms no part of the claimed design. In the drawings, the broken lines depict environmental subject matter only and form no part of the claimed design.
